(57) **CLAIM**

The ornamental design for a grille for an off-road vehicle as shown and described.

DESCRIPTION

FIG. 1 is a top-front-left side perspective view of a grille for an off-road vehicle embodying our new design;

FIG. 2 is an enlarged and partial perspective view thereof, wherein the area of enlargement is region 27 in FIG. 1;

FIG. 3 is a front elevation view thereof;

FIG. 4 is an enlarged and partial perspective view, wherein the area of enlargement is region 29 in FIG. 3;

FIG. 5 is a rear elevation view thereof;

FIG. 6 is a right side elevation view thereof;

FIG. 7 is an enlarged and partial perspective view, wherein the area of enlargement is region 32 in FIG. 7;

FIG. 8 is a left side elevation view thereof;

FIG. 9 is an enlarged and partial perspective view, wherein the area of enlargement is region 34 in FIG. 8;

FIG. 10 is a top plan view thereof; and,

FIG. 11 is a bottom plan view thereof.

The portions of the off-road vehicle shown in broken lines form no part of the claimed design.

1 Claim, 11 Drawing Sheets
